UNITED STATES PATENT OFFICE.

WILLIAM R. BEATTY, OF HAMMOND, INDIANA.

FLOOR-CRANE.

1,333,200.

Specification of Letters Patent.

Patented Mar. 9, 1920.

Application filed February 26, 1919. Serial No. 279,264.

To all whom it may concern:

Be it known that I, WILLIAM R. BEATTY, a citizen of the United States, residing at Hammond, in the county of Lake and State 5 of Indiana, have invented certain new and useful Improvements in Floor-Cranes, of which the following is a specification, reference being had therein to the accompanying drawings.

10 This invention relates to floor cranes, and more particularly to a compact and easily handled crane that can be readily moved to any part of a shop or works by one person.

15 The object of the invention is the improvement in the construction of a floor crane that is readily-movable around a building or shop, and which involves a very unique hoisting device that does not require any ratchets or locks for holding said 20 device in a given position.

Another object of the invention is the construction of a crane which, by reason of its efficient compactness and simplicity 25 of construction, will offer the least friction and which can be easily operated by an individual, not only to manipulate the hoist but also for transferring the crane complete from one place to another place in a 30 works or plant or shop.

With these and other objects in view, my invention comprises certain novel constructions, combinations, and arrangements of parts as will be hereinafter specifically described, illustrated in the accompanying drawings, and more particularly pointed out in the appended claims.

In the drawings,

40 Figure 1 is a view in side elevation of my floor crane.

Fig. 2 is a front view of my floor crane.

Fig. 3 is a horizontal sectional view taken on line 3-3, Fig. 1, looking in the direction of the arrows.

45 Fig. 4 is a fragmentary sectional view of the upper part of the floor crane.

Fig. 5 is a sectional view taken on line 5-5, Fig. 1, looking in the direction of the arrow.

50 Fig. 6 is a perspective view of one of the sections of the worm-casing.

Fig. 7 is a sectional view taken on line 7-7, Fig. 1.

55 Referring to the drawings by numerals, 1 designates the platform or base-structure

of the crane and 2 the standard-structure attached to the base or platform. The platform is substantially the shape of a large U, and in cross section the body is an inverted U or U-shaped, as clearly shown at 60 the ends 3, Fig. 2. The ends 3 are each provided with downwardly-extending lips 4, through which lips 4 extend axles 5. Journaled upon the axles 5, and within the ends 3, are rollers or wheels 6. Integral 65 with the rear central portion of the platform or base-structure 1 is a depending lip 7 through which extends axle 8, and journaled on the axle, near its ends, are rollers or wheels 9. Attached to this axle 8 70 is a handle 10 for pulling or conveying the crane at the will of the operator. The platform or base-structure is provided at opposite sides with integral, depending supports 11 which relieve some of the strain of the 75 load off the rollers or wheels, by reason of the depending supports 11 engaging at their lower ends the floor, but not interfering with the hauling or pulling, through the medium of the handle 10, of the crane over the floor 80 of the shop when desired.

The standard-structure of my crane comprises a base plate 12 that is fastened, through the medium of bolts 13, to the upper face of the platform or base-structure 1, 85 at its rear end. The standard-structure is provided with a tubular-like or main portion 14 that is curved throughout its length, and with a web-like, auxiliary or rear portion 15. The main portion 14 and the auxiliary rear portion 15 are connected by a bracing portion 16. Formed upon the upper end of the rear portion 15 is a bearing 17, and formed upon the upper portion of the forwardly-extending end of the main portion 14 is a bearing 18. Integral with the forwardly-extending or outer end of the main portion 14, on which the bearing 18 90 is formed, are right-angularly disposed flanges or ears 19 for supporting the sectional worm-casing 20.

The sectional worm-casing 20 comprises two similarly-constructed sections, each (Fig. 6) comprising a body portion 21, upper, outwardly-extending apertured ear 22 and lower, outwardly-extending ear 23; a right-angled integral extension 24, constituting an ear, is formed upon the section, and each ear 24 is placed against the similarly-constructed portion or ear 19, and 105 110

through these ears 19 and 24 extend fastening means, such as bolts 25. The ears 22 and 23, of the sections, are placed together. Suitable fastening means such as bolts 26 are extended through these last-mentioned ears for holding the outer portions of the sections together. Extending through the bodies 21 of the sections, constituting the worm-casing, is a shaft 27, and fixedly secured to this shaft, within the worm-casing, is a gear 28. Journaled in the bearings 17 and 18 is a driving shaft 29, which driving shaft extends partly through the worm-casing, and has the worm 30 formed thereon within the casing, which worm 30 meshes with the gear 28 (Fig. 4). On the outer end of the driving shaft 29 is positioned a pulley or gear wheel 31 upon which is positioned a chain 32, so that the operator can pull on the chain and rotate or "drive" shaft 29 for operating the worm 30 and gear 28. Upon the gear 28 being rotated, similar movement will be imparted to the shaft 27, and the pulleys or gear wheels 33, fixedly secured to shaft 27, will be rotated, thereby causing the chain 34 to be raised or lowered, depending upon the direction of rotation of shaft 29, resulting in the manipulation of the plate or block 35 carrying the hoisting hook 36.

It is to be understood that the operator grasps the chain 32 and pulls on the same to rotate the wheel or gear 31, thus imparting a rotary movement to the wheels or gears 33 resulting in the raising or lowering of the hook 36 that may be attached to the load to be raised or lowered. Upon the operator releasing chain 32, the hoist will be instantly stopped in its travel and remain in the adjusted position without any additional locking means other than the worm and gear structure of the crane. My improved crane offers the least amount of friction; is simple and compact in construction, and owing to its efficiency and simplicity, it can be manufactured at a minimum cost.

I wish it to be understood that I reserve the right to make certain minor alterations and changes as shall appear to one skilled in the art to which this invention relates, which changes or alterations fairly fall within the scope of the appended claims.

It is obvious, of course, that my crane may be operated by motor power or in any other manner.

What I claim is:

1. In a floor crane, the combination with a base-structure, of a standard-structure mounted upon said base-structure, said standard-structure provided at its upper, outer end with a detachable sectional, worm-casing, a hoisting device including a worm carried by said casing, the worm positioned in said casing, and manually operable

means supported upon said standard-structure and connected with said worm for operating the hoisting device.

2. In a floor crane, the combination with a base-structure, of a standard-structure supported upon said base-structure, said standard-structure provided at its upper outer end with oppositely-extending ears, a worm-casing provided with oppositely-extending ears, the last-mentioned ears being positioned against the oppositely-extending ears of the standard-structure, fastening means in said engaging ears for holding the worm-casing upon the standard-structure, a worm in said casing, hoisting means supported upon said casing and coöperating with said worm, and means for driving the worm for operating the hoisting means.

3. In a floor crane, the combination with a base-structure, of a standard-structure carried by said base-structure, said standard-structure provided at its outer forward end with an integral bearing and with right-angularly positioned integral flanges or ears, a sectional worm-casing positioned against said ears, each section of said casing comprising a hollow body and an upper and a lower outwardly-extending ear and also with a right-angularly positioned ear, the right-angularly positioned ears of the sections positioned against the first-mentioned ears of the standard-structure, detachable fastening means in all of the engaging ears for securing the sections of the worm-casing together and the worm-casing to the ears of the standard-structure, a shaft journaled in the bearing of the standard-structure and provided with a worm in the worm-casing, a shaft extending through the sections of the worm-casing and being provided with a gear in the worm-casing meshing with the worm of the first-mentioned shaft, wheels or gears on the shaft of the worm-casing, a chain on these wheels, a hook suspended from said chain, and means for driving the first-mentioned shaft for operating the worm and its coöperating parts.

4. In a floor crane, the combination with a base-structure, of a standard structure including a base plate resting upon the base-structure and a tubularlike curved main portion and an integral, rear, web-like portion secured to the base-plate, means detachably connecting the base plate to the base structure, bearings formed upon the top of said web-like portion and said tubularlike portion, lifting or hoisting means supported at the forward end of said tubularlike portion, a driving shaft journaled upon said bearings and operably connected to said lifting or hoisting means, and manually operable means connected to said driving shaft for operating the same.

5. In a floor crane, the combination with

a base-structure, of a standard-structure supported upon said base-structure, said standard-structure including a base plate and a forwardly-extending tubular-like portion secured at its lower end to said plate and integral with said tubular-like portion a rear web-like portion, means detachably securing the base plate to the base-structure, and hoisting or lifting means supported 5 upon said tubular-like and web-like portions.

6. In a floor crane, the combination with a base structure, of a plate resting upon said base structure, a forwardly-extending hollow portion secured to said plate, said portion provided with an upper outer end, a rear bracing portion connected to said hollow portion near its upper and lower ends, and hoisting means supported at said upper 10 per outer end of the hollow portion.

7. In a floor crane, the combination with

a base structure, of a plate resting upon said base structure, a tubular-like portion integral with the plate and extending forwardly and provided with an upper outer end, an 25 integral bracing frame-like structure extending rearwardly from the tubular-like portion, and hoisting means carried upon the upper outer end of the tubular-like portion.

8. In a floor crane, the combination with a base structure, a plate detachably mounted upon the base structure, of a forwardly-extending hollow portion integral with the plate, web and bracing means in the rear 35 of said hollow portion and connected to the same near its upper and lower ends, and hoisting means carried by the upper end of said hollow portion.

In testimony whereof I hereunto affix my 40 signature.

WILLIAM R. BEATTY.
